UNITED STATES PATENT OFFICE

94,902

DESIGN FOR A SHOE OR ARTICLE OF ANALOGOUS NATURE

Raymond H. Jackson, Amesbury, Mass., assignor
to Jackson, Miller & Wilde, Inc., Merrimac,
Mass., a corporation of Massachusetts

Application January 22, 1935, Serial No. 54,991

Term of patent 3½ years

To all whom it may concern:

Be it known that I, Raymond H. Jackson, a citizen of the United States, and a resident of Amesbury, in the county of Essex and Commonwealth of Massachusetts, have invented a new, original, and ornamental Design for a Shoe or Article of Analogous Nature, of which the following is a specification, reference being had to the accompanying drawing, forming a part thereof.

In the accompanying drawing, Figure 1 is a view in plan and Fig. 2 is a view in side elevation of a shoe showing my new design, a conventional

heel, sole and lacing being indicated thereon by dotted lines.

The dominant feature of my design for a shoe resides in the ornamental effect produced by its upper, as will be recognized from the drawing, it being understood that when viewed from either side the upper presents substantially the same appearance.

I claim:

The ornamental design for a shoe or article of analogous nature, substantially as shown and described.

RAYMOND H. JACKSON.
